UNITED STATES PATENT OFFICE

2,674,737

MACHINE FOR DISPENSING AND PLACING
FENCING WIRE STAPLES

Woodrow W. Patterson, Nashville, Tenn.

Application August 14, 1952, Serial No. 304,359

8 Claims. (Cl. 1—49.8)

1

This invention relates to new and useful improvements in staple holders and dispensers, and the primary object of the invention is to provide a device for holding and dispensing fencing wire staples so that the staples may be driven into a fence post or the like in a convenient manner.

Another important object of the present invention is to provide a fencing wiring staple holder and dispenser involving a manually rotated pick-up member having means thereon for engaging and retaining a staple so that the staple may be driven into a supporting structural element.

A further object of the present invention is to provide the aforementioned rotatably pick-up member with a magnet that will attract and hold a staple relative thereto and an elongated tubular guide forming part of the dispenser that will slidably guide staples toward the magnet as the pick-up member is rotated.

A still further aim of the present invention is to provide a device for dispensing and placing fencing wire staples and is extremely simple and practical in construction, small and compact in structure, inexpensive to manufacture, efficient and durable in operation, convenient to actuate and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of the present invention in a normal position;

Figure 2 is a side elevational view of Figure 1 and with parts of the guide broken away for the convenience of explanation;

Figure 3 is a view similar to Figure 1 but showing the pick-up member rotated to engage a staple at the discharge end of the guide;

Figure 4 is an enlarged fragmentary bottom plan view of Figure 1;

Figure 5 is an enlarged detail view taken substantially on the plane of section line 5—5 of Figure 1 but showing a staple held relative to the pick-up member;

Figure 6 is a vertical sectional view taken substantially on the plane of section line 6—6 of Figure 4;

Figure 7 is an enlarged fragmentary view of Figure 3 and with parts of the guide broken away and shown in section for the convenience of explanation;

Figure 8 is an enlarged detailed vertical sec-

2

tional view taken substantially on the plane of section line 8—8 of Figure 1 and showing in dotted lines the position of the combined closure and pusher cap element for the loading of staples into the guide; and

Figure 9 is an enlarged detail transverse vertical sectional view taken substantially on the plane of section line 9—9 of Figure 1.

Referring now to the drawings in detail, where-in for the purpose of illustration, there is disclosed a preferred embodiment of the present invention, the numeral 10 represents an elongated tubular guide having a forward discharge end 12 and a rear receiving end 14. The guide 10 comprises inner and outer longitudinal channels 16 and 18 whose walls are spaced apart to form a U-shaped passage 20 (Figure 8) that will accommodate a plurality of fencing wiring staples S. The side walls of the channels 16 and 18 are provided with outturned flanges 22 and 24 that are held in juxtaposition by connecting fasteners 26.

Fasteners 26 also are engaged with a rigid support bar 28 having a forward upwardly offset portion 30 that is disposed in front of the discharge end 12 and parallel to the channels 16 and 18. Offset portion 30 is pivotally secured to a holding member or pick-up plate 32 by a pivot 34 that extends perpendicular to the channels 16 and 18.

The curved edge 36 of plate 32 is formed with a peripheral notch 38 that is bridged by a resilient bumper strip 40. The bumper strip 40 is secured to the upper face of the pick-up plate 32 by rivets or the like 42 and overlies the upper flange 44 of an angle magnet 46 that is secured to plate 32 by a fastener 48. The flange 50 of magnet 46 is bifurcated and extends through notch 38 to engage and attract the limbs of a staple S thereto as the plate 32 is rotated to bring the notch 38 into registry with discharge end 12.

A plate element 52 is removably secured to the undersurface of plate 32 and includes a L-shaped finger 54 that underlies the notch 38. The finger 54 is provided with a free end portion 56 that projects outwardly beyond the edge 36 of plate 32 to engage a staple in a manner presently to be described.

A supporting bracket 58 is supported on the guide 10 by one of the fasteners 26 and is pivotally secured to an intermediate portion of a substantially L-shaped lever 60 by a pin 62 that parallels pivot 34. The forward end 64 of lever 60 has a pivoted connection, as at 66, to one end

55 60 has a pivoted connection, as at 66, to one end

of a pitman or link 68. The other end of pitman 68 is pivotally attached, as at 48, to the plate 32 eccentric of pivot 34 so that as the hand-gripping portion 72 of the lever 60 is pulled toward the guide 10, the plate 32 will swing or rotate to move notch 38 toward end 12 (compare Figures 1 and 3). A coil spring 74, terminally secured to lever 60 and an anchor 76, supported on guide 10, yieldingly urges the forward limb of lever 60 toward the guide 10, as shown in Figure 1. A stop flange 77 is formed at the forward end 64 of the lever 60 and will engage the rear end of pitman 68 as shown in Figure 1 when the device is being carried.

The rear end of channel 16 projects rearwardly beyond the rear end of channel 18 to receive a closure cap element 78. Coil springs 80 are terminally attached to elements 78 and the guide 10 to yieldingly urge the cap element 78 forwardly over the rear end of channel 16, as shown in Figure 8.

Inverted U-shaped supporting brackets 82 are secured to the flanges 22, 24 and these brackets 82 engage a longitudinal hand-grip 84. Bolts 86 carried by the supporting brackets 82 extend under the ends of the hand-grip 84 and are adjusted to clamp the brackets 82 against the end portions of the hand-grip 84.

In practical use of the present invention, the cap element 78 is pulled rearwardly past the rear end of channel 16 and then slid downwardly to be retained in this position, shown by dotted lines in Figure 8, until a suitable number of staples S have been inserted into the guide 10 and over the channel 16. Then, the cap element 78 is lifted and allowed to move forwardly by the action of springs 80. The staples S slide downwardly between the channels 16 and 18 when the tubular guide 10 is tilted downwardly. The tubular guide 10 may be tilted to approximately 45° to assure the sliding movement of the staples S. The staples are attracted by magnet 46 for positioning the staples for engagement by the finger 54.

As shown best in Figure 2 of the drawings, the pick-up plate 32 extends across the discharge end 12 of the guide 10 so that staples S urged forwardly by the cap element 78 or by gravity when the guide 10 is held in a vertically inclined position, cannot pass from the discharge end 12.

As the hand-gripping portion 72 of lever 60 is pulled inwardly toward the guide 10, pivot 48 is rotated in a clockwise direction toward the discharge end 12. As the notch 38 approaches the discharge end 12, the free end portion 56 of finger 54 will engage behind the forwardmost of the staples S and guide this staple toward the magnet 46. The finger 54 also prevents more than one staple S from being engaged and attracted to the magnet 46 at one time.

As the hand-gripping portion 72 of lever 60 is released, the spring 74 will return the plate 32 to its initial position as shown in Figure 1 and the staple engaged with the magnet 46 will also be moved forwardly so that a hammer or striking element can be employed for driving the staple into a fence post or the like. The bumper strip 40 will prevent the striking element or hammer from engaging the pick-up member 32 to bend or harmfully effect the same.

The hand-gripping portion 84 is disposed relatively close to the gripping portion 72 of lever 60 so that a user grasping portion 84 in his hand may extend his fingers outwardly to engage the portion 72 to pull the latter to the guide 10. In

this manner, the dispensing and placing device is readily manipulated by one hand of an operator leaving the other hand free to handle a striking element or hammer that will be employed for driving the staple when it is moved to its forward position. Counter-clockwise rotation of the pick-up member 32 may be limited by manipulation of the hand-gripping portion 72 in the event it is desired to drive the staple before it reaches its maximum forward position, shown in Figure 1.

Having described the invention, what is claimed as new is:

1. A holder and dispenser for fence wire staples, said holder and dispenser comprising an elongated tubular guide adapted to slidably receive a plurality of staples therein, said guide having a discharge end, a support carried by said guide and having a forward end portion in front of the discharge end of the guide, a rotatable holding member on the forward end of said support and having means thereon for movement across said discharge end to engage and carry a staple to a position for driving, and means attached to the guide and connected to the member for rotating the latter, said staple engaging and carrying means including a pick-up finger and a magnet adapted to attract a staple engaged by said finger.

2. A holder and dispenser for fence wire staples, said holder and dispenser comprising an elongated tubular guide adapted to slidably receive a plurality of staples therein, said guide having a discharge end, a support carried by said guide and having a forward end portion in front of the discharge end of the guide, a rotatable holding member on the forward end of said support and having means thereon for movement across said discharge end to engage and carry a staple to a position for driving, and means attached to the guide and connected to the member for rotating the latter, said means on said holding member for movement across said discharge end including a magnet and a pick-up finger extending outwardly from the magnet to guide a staple toward the magnet.

3. A holder and dispenser for fence wire staples, said holder and dispenser comprising an elongated tubular guide adapted to slidably receive a plurality of staples therein, said guide having a discharge end, a support carried by said guide and having a forward end in front of the discharge end of the guide, a holding plate pivoted to the forward end of said support and paralleling the tubular guide, said plate being rotatable on the support and having an edge extending across the discharge end of said guide to block passage of a staple from said discharge end, said plate having a notch in said edge to accommodate a staple, means carried by the plate for entering the discharge end and for urging a staple into said notch as the latter moves into registry with said discharge end during rotation of said plate, means carried by said plate at said notch for retaining a staple relative to the plate and within the notch, and means attached to the plate for rotating the same.

4. A holder and dispenser for fence wire staples, said holder and dispenser comprising an elongated tubular guide adapted to slidably receive a plurality of staples therein, said guide having a discharge end, a support carried by said guide and having a forward end in front of the discharge end of the guide, a holding plate pivoted to the forward end of said support and paralleling the tubular guide, said plate being rotatable on

the support and having an edge extending across the discharge end of said guide to block passage of a staple from said discharge end, said plate having a notch in said edge to accommodate a staple, means carried by the plate for entering the discharge end and for urging a staple into said notch as the latter moves into registry with said discharge end during rotation of said plate, means carried by said plate at said notch for retaining a staple relative to the plate and within the notch, a lever pivotally attached to the guide, and a pitman eccentrically pivoted to the plate and pivotally attached to one end of the lever.

5. A holder and dispenser for fence wire staples, said holder and dispenser comprising an elongated tubular guide adapted to slidably receive a plurality of staples therein, said guide having a discharge end, a support carried by said guide and having a forward end portion in front of the discharge end of the guide, a holding plate 20 pivoted to the forward end of said support and paralleling the tubular guide, said plate being rotatable on the support and having an edge extending across the discharge end of said guide to block passage of a staple from said discharge end, said plate having a notch in said edge to accommodate a staple, means carried by the plate for entering the discharge end and for urging a staple into said notch as the latter moves into registry with said discharge end during rotation of said plate, means carried by said plate at said notch for retaining a staple relative to the plate and within the notch, a lever pivotally attached to the guide, and a pitman eccentrically pivoted to the plate and pivotally attached to one end of the lever, said one end of said lever having a stop flange thereon engageable with said pitman during rotation of said plate to bring said notch into registry with said discharge end to limit relative movement between the lever and the pitman.

6. A holder and dispenser for fence wire staples, said holder and dispenser comprising an elongated tubular guide adapted to slidably receive a plurality of staples therein, said guide having a discharge end, a support carried by said guide and having a forward end in front of the discharge end of the guide, a rotatable holding member on the forward end of said support and having means thereon for movement across said discharge end to engage and carry a staple to a position for driving, and means attached to the guide and connected to the member for rotating the latter, said guide also having an entrance end, and a removable cap resiliently connected to said guide and adapted to permit a stack of 55 staples to be inserted within the guide.

7. A holder and dispenser for fence wire staples, said holder and dispenser comprising an elongated tubular guide adapted to slidably receive a plurality of staples therein, said guide having a discharge end, a support carried by said guide and having a forward end in front of the discharge end of the guide, a holding plate pivoted to the forward end of said support and paralleling the tubular guide, said plate being rotatable on the forward end of support and having an edge extending across the discharge end of said guide to block passage of a staple from said discharge end, said plate having a notch in said edge to accommodate a staple, means carried by the plate for entering the discharge end and for urging a staple into said notch as the latter moves into registry with said discharge end during rotation of said plate, means carried by said plate at said notch for retaining a staple relative to the plate and within the notch, and means attached to the plate for rotating the same, and a resilient bumper strip secured to said plate over the notch to shield the plate from a striking element used for driving a staple held in said notch.

15 8. A holder and dispenser for fence wire staples, said holder and dispenser comprising an elongated tubular guide adapted to slidably receive a plurality of staples therein, said guide having a discharge end, a support carried by said guide and having a forward end in front of the discharge end of the guide, a holding plate pivoted to the forward end of said support and paralleling the tubular guide, said plate being rotatable on the forward end of said support and having an 25 edge extending across the discharge end of said guide to block passage of a staple from said discharge end, said plate having a notch in said edge to accommodate a staple, means carried by the plate for entering the discharge end and for urging a staple into said notch as the latter moves into registry with said discharge end during rotation of said plate, means carried by said plate at said notch for retaining a staple relative to the plate and within the notch, and means attached to the plate for rotating the same, and a resilient bumper strip secured to said plate over the notch to shield the plate from a striking element used for driving a staple held in said notch.

30 9. A holder and dispenser for fence wire staples, said holder and dispenser comprising an elongated tubular guide adapted to slidably receive a plurality of staples therein, said guide having a discharge end, a support carried by said guide and having a forward end in front of the discharge end of the guide, a holding plate pivoted to the forward end of said support and paralleling the tubular guide, said plate being rotatable on the forward end of said support and having an 35 edge extending across the discharge end of said guide to block passage of a staple from said discharge end, said plate having a notch in said edge to accommodate a staple, means carried by the plate for entering the discharge end and for urging a staple into said notch as the latter moves into registry with said discharge end during rotation of said plate, means carried by said plate at said notch for retaining a staple relative to the plate and within the notch, and means attached to the plate for rotating the same, and a resilient bumper strip secured to said plate over the notch to shield the plate from a striking element used for driving a staple held in said notch.

40 10. A holder and dispenser for fence wire staples, said holder and dispenser comprising an elongated tubular guide adapted to slidably receive a plurality of staples therein, said guide having a discharge end, a support carried by said guide and having a forward end in front of the discharge end of the guide, a holding plate pivoted to the forward end of said support and paralleling the tubular guide, said plate being rotatable on the forward end of said support and having an 45 edge extending across the discharge end of said guide to block passage of a staple from said discharge end, said plate having a notch in said edge to accommodate a staple, means carried by the plate for entering the discharge end and for urging a staple into said notch as the latter moves into registry with said discharge end during rotation of said plate, means carried by said plate at said notch for retaining a staple relative to the plate and within the notch, and means attached to the plate for rotating the same, said means for entering the discharge end of said guide comprising a resilient finger having a free end portion projecting outwardly beyond said edge.
